TUBE HOLDER

George Dewey Walker, Riveredge, and Clarence Emerson Oulsnam and Frydryak Krysa, Jersey City, N. J., assignors to Colgate-Palmolive-Peet Company, Jersey City, N. J., a corporation of Delaware

Application January 20, 1944, Serial No. 518,970

9 Claims. (Cl. 248—108)

The present invention relates to tube holders for tube filling and closing machines.

Collapsible tubes containing tooth paste, shaving cream, and similar materials of a plastic nature are filled and closed in automatic machines. While there are a number of different types of such machines in commercial use, they all comprise tube holders which are designed to hold the tubes with the cap ends down and to move the tubes to the various stations for filling, closing, etc. The tube holders ordinarily are moved stepwise along a track or guide in a closed course or orbit. In the operation of these machines, the cap ends of the empty tubes are inserted, either automatically or manually, into the holders at a loading station. The loaded holders move to a filling station, where the liquid or plastic material is flowed into the tube through the open upper end. In order to fill the tubes satisfactorily, it is necessary that the nozzle of the filling device move into the tube until it is near the cap end before the material is flowed through it into the tube, and that it move outwardly as the tube fills until it is clear of the tube. This relative motion is obtained in some machines by mounting the nozzle for vertical motion into and out of a stationary tube and in other machines by moving the tube holder at the filling station toward and away from a stationary nozzle. In either case, after the tube has been filled the holder with the filled tube advances to a closing station where the end of the tube is folded over and crimped or a clip applied. The closing of the tube may require several successive operations at different stations. The holder with the filled and closed tube then moves to a pick-out station where an automatic picker grasps the closed end of the tube to lift it out of the holder and place it on a conveyor which carries it to a cartoning machine.

Satisfactory operation of such automatic filling and closing machines requires that the tube be held in accurate position when the holder stops at the filling, closing and pick-out stations. If a tube is not properly positioned, for example when the nozzle descends into the tube, the wall of the tube may be crushed and the contents spilled into the holder and onto the track, thus causing delays while the machine is stopped for cleaning. Similarly, if the tube is not held in proper position at the closing station, an imperfect crimp results. At the pick-out station, if the tubes are not in proper position, the pickers may damage the tube and/or fail to remove it.

The tube holders of the prior art comprise a re-

ceptacle having a cylindrical bore corresponding approximately to the outside diameter of the tubes to be placed therein, a shoulder or flange at the bottom of the bore upon which the shoulder of the tube rests, and a recess for the cap. Tubes of a given size vary considerably in outside diameter, so that the receptacle cannot be relied upon properly to receive and accurately to position all tubes of a given size. Thus, a tube of somewhat larger diameter than the receptacle is designed to hold properly would fit too tightly for satisfactory operation, whereas a somewhat smaller tube would wobble around in the receptacle and not be positioned accurately for filling, closing or picking from the receptacle. One expedient which has been widely used in an attempt to overcome this difficulty was to make the bore large enough to take the largest tubes of a given size and to provide resilient means adapted to bear against the outside wall of the tube, e. g., a leaf spring fastened at one end to the outside wall of the receptacle with the other end extending into the bore through a slit in the wall. Using such springs, reasonably satisfactory positioning of the tubes could be obtained, provided the external diameter of the tubes did not vary more than plus or minus 0.005 inch from a specified size for which the holder was designed. The leaf springs, however, often scratched the end of the tube inserted into the receptacle, and in cases where the tubes were filled a little too full, the closing operation caused them to swell and bind in the receptacle. When the automatic pickers exerted an upward force against the crimped end of such tubes, the crimped end often tore open, or the walls of the tube were fractured.

It is an object of the present invention to provide a tube holder into which tubes deviating considerably from specified size can be readily inserted, which will accurately hold tubes in an upright position for filling and closing, and which will not bind even swollen tubes against the withdrawal force of automatic pickers.

Other objects and advantages of the invention will be apparent from the following description of the invention taken in conjunction with the drawing, in which Fig. 1 is an elevation of a two-receptacle tube holder and Fig. 2 is a vertical sectional view along the line 2—2 of Fig. 1.

Referring now more particularly to the drawing, reference numeral 2 designates a tube holder having a base plate 4 and two tube receptacles 6. Holders of this general design are used in one type of commercial automatic filling and closing machine. The base plate 4 extends a short dis-

tance beyond the walls of the tube receptacle 6, providing a flange which cooperates with the track of the automatic filling and closing machine to maintain the tube holder in proper position in the machine. In another type of such machines the tube holders are made separable from the base plates to which they are secured by threaded fasteners, tapered plugs and sockets, or the like. The type of holder shown in the drawing is used for illustrating the invention 10 and not by way of limitation.

Each tube receptacle 6 comprises a base 8 having a recess 9 large enough to accommodate the cap of the tube which will be placed therein as illustrated by the dashed outline. Surrounding the recess 9 is a shoulder 10 which is preferably beveled on the same angle as the shoulder of the tube which will be used in the holder. Above the shoulder 10 is a retaining wall 12 of cylindrical shape and having an internal radius of curvature slightly longer than half the outside diameter of the tubes to be used therein. While it is preferred to provide a shoulder 10, it is not essential and the inward motion of the tube into the receptacle may be limited by contact of the cap with the bottom of the recess 9.

The retaining wall 12 comprises a plurality of segments which are movable relative to each other. Satisfactory results have been obtained with a retaining wall comprising two substantially semi-cylindrical segments. One of these segments, 14, is preferably fixed and may be integral with the base 8. The other is a movable segment 16 which may be hinged to the base 8. Resilient means are provided for urging the movable section inwardly toward the fixed section. One of the sections preferably is somewhat less than a semi-cylinder, so that when the movable section is in closed position, as shown in Fig. 2, the bore of the receptacle departs slightly from and is somewhat smaller than a true circle of the same radius of curvature. In this way a receptacle is provided which satisfactorily holds and positions tubes within the tolerance of plus or minus 0.02 inch. Moreover, even though the tube is caused to swell in the closing operation, the wall of the receptacle yields readily enough to permit the pickers to remove the tube without damaging the crimp or deforming the tube.

In a preferred embodiment of the invention, the movable section 16 is secured to the base 8 by a leaf spring 18 which serves the dual function of the hinge and resilient means for urging the movable section to a closed position. The leaf spring may advantageously be set in aligned grooves 20 in the movable segment 16 and the base 8, as illustrated in Fig. 1, although this is not essential if a plurality of fasteners 22 are used as illustrated in Fig. 1 for securing the leaf spring to both the base and the movable segment.

A simple way to make the tube holders embodying the present invention is to cast or mold the holder in integral form from a suitable metal, alloy, plastic, or the like, and to cut the movable segment along the lines shown in Fig. 2 with a hack saw. The saw kerf removes sufficient material from the receptacle wall to provide for the offset from the true circular shape referred to above.

Although the invention has been described in considerable detail in connection with certain preferred embodiments, it will be understood that

modifications and variations within the scope of the appended claims are contemplated.

We claim:

- 5 1. A tube holder comprising a base and a receptacle thereon having a bore surrounded by a wall, said wall comprising sections movable relative to each other to vary the cross-section of the bore, at least one of said sections being hinged to said base, and means yieldingly urging said sections to closed position.
- 10 2. A tube holder comprising a base having a recess surrounded by a shoulder of fixed size adapted to support the shoulder of a tube in said holder, and a retaining wall above and around said shoulder, said retaining wall comprising sections movable relative to each other to vary the cross-section of the bore formed by said wall sections, and means yieldingly urging said sections to closed position.
- 15 3. A tube holder comprising a base and a receptacle thereon having a bore surrounded by a wall, said wall comprising a fixed section and a movable section, said movable section being mounted on said base by a leaf spring yieldingly urging the movable section toward the fixed section.
- 20 4. A tube holder comprising a base having a recess surrounded by a shoulder of fixed size adapted to support the shoulder of a tube in said holder, and a retaining wall above and around said shoulder, said retaining wall comprising a fixed section and a movable section, and means yieldingly urging the movable section toward the fixed section.
- 25 5. A tube holder comprising a base having a recess, a shoulder surrounding said recess, and a retaining wall above said shoulder, said retaining wall comprising a fixed section and a movable section, and a leaf spring securing said movable section to said base.
- 30 6. A tube holder comprising a base having a recess, a shoulder surrounding said recess, and a retaining wall above said shoulder, said retaining wall comprising a fixed section and a movable section, said base and said movable section having aligned grooves, and a leaf spring having a width corresponding to the width of said grooves secured in said grooves.
- 35 7. A tube holder comprising a base plate, two tube receptacles on said plate, each receptacle comprising a base having a recess, a shoulder surrounding said recess, and a retaining wall above said shoulder, said retaining wall comprising sections movable relative to each other, and means yieldingly urging said sections inwardly.
- 40 8. A tube holder comprising a fixed section having a substantially semi-cylindrical recess, a movable section having a substantially semi-cylindrical recess, and a leaf spring mounting said movable section in mating relation to said fixed section to form a receptacle.
- 45 9. A tube holder comprising a sectional wall defining a receptacle of variable cross-section, a shoulder of fixed dimensions below said sectional wall adapted to support the shoulder of a tube in said receptacle, and means yieldingly urging said wall sections to a position of minimum cross-section.
